RAFT

Martin E. McClure, Bloomfield Hills, Mich., assignor to Diversified Glass Products, Inc., Rochester, Mich.

Filed Mar. 31, 1971, Ser. No. 130,052

Term of patent 14 years

Int. Cl. 21—03
U.S. Cl. D71—1 HH

FIG. 1

FIG. 2

FIG. 4

FIG. 3

FIG. 5

FIG. 1 is a perspective view of a raft, showing my new design;

FIG. 2 is a top plan view thereof;

FIG. 3 is a side elevational view thereof as seen from line 3—3 of FIG. 2;

FIG. 4 is a bottom plan view; and

FIG. 5 is a top plan view of a modification thereof, the side view and bottom whereof being respectively as FIGS. 3 and 4.

I claim:

The ornamental design for a raft, as shown and described.
